UNITED STATES PATENT OFFICE.

HERMAN L. DOUVE, OF DANVILLE, ILLINOIS.

DIFFERENTIAL MECHANISM.

Application filed November 3, 1922. Serial No. 598,836.

This invention relates to motor operated vehicles, and has particular application to a differential mechanism therefor, wherein a positive two-wheel drive is provided, and the power equally transmitted to both wheels under all conditions, thus eliminating the spinning of one wheel in advance of the other which is an objectionable feature of similar mechanisms in present day use.

In carrying out the invention, I provide a mechanism wherein the power is not entirely spent on the wheel offering the least resistance, said mechanism including special cooperating elements which are adapted to automatically move into and out of interlocking relation, incident to the necessary change in operation of the mechanism, the latter being simple in construction, both readily understandable and accessible.

Other objects and advantages will appear when the following detailed description is read in connection with the accompanying drawings, the invention residing in the construction, combination and arrangement of parts as claimed.

In the drawings forming part of this application, the like numerals of reference indicate similar parts in the several views, and wherein:

Figure 1 is a vertical sectional view through a wheel showing the differential mechanism in the hub thereof, and the parts in the positions occupied incident to the forward movement of the wheel.

Figure 2 is a similar view showing the position of the parts incident to the rearward movement of the wheel.

Figure 3 is a sectional view taken on line 3-3 of Figure 2.

Figure 4 is a sectional view taken on line 4-4 of Figure 1.

Figure 5 is a plan view of the cooperating toothed annuli.

Figure 6 is a view in elevation of the floating ring.

Figure 7 is an end elevation of the sleeve arranged within the hub and surrounding the driving shaft.

Figure 8 is a similar view of the cap carried by the driving shaft and cooperating with the sleeve.

Figure 9 is a detail view of one of the supporting elements for the floating ring.

Figure 10 is a fragmentary elevation of the worm element embodied in the invention.

Referring to the drawings in detail, A indicates generally the hub of the wheel, which includes the member 10 and the oppositely disposed annuli 11 which are arranged and secured to the member 10 by means of the bolts or other suitable fastening elements indicated at 12. The member 10 has also associated therewith a hub cap 13. The wheel is in the nature of a disk which is indicated at 14, and is clamped between the member 10 of the hub and the brake drum 15 as clearly illustrated in Figure 1. The disk is provided with a circumferentially disposed series of openings 16 which receive the projections 17 carried by the member 10 of the hub. The hub in its entirety houses the differential mechanism forming the subject matter of the present invention, it being understood that one mechanism is arranged in the hub of each of the traction wheels of the motor operated vehicle, (not shown), the said traction wheels being associated by a one-piece axle 18 positioned within the usual axle housing indicated at 19. This mechanism will be hereinafter fully described, it being the purpose of the mechanism, as above pointed out to provide a positive two wheel drive, and to equalize the distribution of the power to both wheels under all conditions, thus eliminating the spinning of one wheel in advance of the other which frequently occurs with mechanisms in present day use. In other words, the invention eliminates transmission of all the power to the wheel offering the least resistance, and on the contrary distributes such power to both wheels so that the latter are positively driven.

The differential mechanism embodies a sleeve 21 which is arranged in spaced concentric relation to the axle housing 19. The portion 22 of this sleeve is octagonal, while the reduced portion indicated at 23 is of cylindrical formation and embraced by the member 10 of the hub. The sleeve 21 is supported by roller bearings 24 which are fixed upon the axle housing at spaced points, and received by cone-shaped members 25 which are carried on the interior of the sleeve 21. The outer end of this sleeve is provided with a circumferential series of teeth 26, which cooperate with the teeth 27 of a cap 28. The cap 28 is provided with a squared opening 29 to accommodate the squared portion 30 of the driving shaft 18, and is held asso-

ciated therewith by means of a nut 31 threaded upon the threaded extremity 32 of said shaft. This cap is provided with an annular flange 33 which bears against the adjacent roller bearings 24, so that when the cap is adjusted longitudinally of the shaft, the bearings and said sleeve are moved or adjusted in the same direction.

Mounted upon the octagonal shaped portion 22 of the sleeve, is a ring 34 or annulus, which of course turns with this sleeve, and this ring in part assists in supporting the floating ring utilized to automatically shift certain parts of the mechanism to change the direction of rotation of the traction wheels, in a manner to be hereinafter described. The floating ring 35 is clearly illustrated in Figure 6 of the drawing, wherein it will be noted that the outer periphery of this ring is provided with spaced notches 36 which receive the right angularly disposed extensions 37 which project from the rods 38 at points approximately midway between the ends thereof. The rods 38 are mounted to slide through the openings in the ring 34 and are arranged at diametrically opposite points about this ring as clearly illustrated in Figure 4. Projecting from the inner periphery of the floating ring 35 is an annular series of pins 39, each of which supports a tapered roller 40. These rollers cooperate with a worm gear 41 fixed upon the axle housing 19, which will control the automatic shifting of the elements above referred to. The rods 38 project from both sides of the ring 34, and surrounding the projected portions of these rods are coiled springs 42 and 43 respectively. These springs are alternately compressed and function to hold the floating ring 35 on one or the other side of the worm gear 41.

Upon inspection of Figure 5, it will be noted that the ring 34 is arranged between the spaced rings or annuli 44 and 45 respectively, and adapted to be moved into interlocking relation with either one or the other of the spaced rings, depending of course upon the particular direction of rotation of the wheels. For this purpose, the ring 34 is provided with teeth 46 at opposite sides thereof, the teeth on one side being reversely disposed with respect to the teeth at the opposite side of the ring for a purpose to be presently described. The ring 44 is provided with teeth 47 adapted to cooperate with the teeth on the adjacent side of the ring 34, while the ring 45 is provided with teeth 48 adapted to cooperate with the teeth on the adjacent side of the intermediate ring 34.

As above pointed out, the ring 34 is mounted for rotation with the sleeve 21, but is also susceptible of sliding movement longitudinally of the sleeve, in order to bring it into interlocking association with either of the

rings 44 and 45. The latter mentioned rings are however fixed to the hub of the wheel, and when the ring 34 is interlocked with the ring 44, the wheels rotate in a forward direction. When the intermediate ring 34 is interlocked with the ring 45, the wheels are rotated in a reverse direction. As shown in Figure 1, the rings 44 and 45 are arranged within the annular shaped members in cross section indicated at 11 and which form a part of the hub proper.

It will also be pointed out, that the rings 44 and 45 are mounted upon driven journals 50 which rotate with the sleeve 21. These journals have ball bearings or the like at 51 to minimize friction. The bearings 50 are provided with openings 52 which align with bores 53, thereby making it possible to lock the rings 44 and 45 to the bearings, by means of a suitable locking pin or key, in event that this particular portion of the mechanism becomes impaired for any reason whatsoever.

The mechanism forming the subject matter of the invention operates as follows:

When the traction wheels are to be moved in a forward direction, the component parts of the mechanism occupy the positions illustrated in Figure 1. In other words, the intermediate ring 34 has its teeth at one side thereof meshing with the teeth 47 of the ring 44, with the floating ring 35 to the left of the worm gear 41.

It will be further noted that the rollers 40 carried by the floating ring 35 are also slightly spaced from one side of the worm gear 41, and that the springs 42 associated with the sliding rods 38 are compressed. While these springs 42 are under compression, and tend to shift the rods 38 together with the floating ring 35 in the direction of the worm gear, this is obviated by reason of the angularity of the teeth 46 of the intermediate ring, and the angularity of the teeth 47 of the ring 44 which is now interlocked with the intermediate ring.

In other words, as the wheels continue to rotate in a forward direction, the angularity of the teeth as above described, moves the intermediate ring 34, or in other words, holds this ring in proper interlocking relation with the ring 44. By reason of the fact that the power from the driving shaft 18 is equally transmitted to both traction wheels, it follows that neither wheel can rotate any slower than the rotation of the driving shaft 18, but a differential action of either wheel is permitted as the occasion requires. This is permitted, by reason of the angularity of the teeth on the various rings above referred to, which allows the ring associated with the particular wheel to be accelerated, to ratchet over the intermediate ring 34. In turning a curve, the inner wheel cannot rotate any faster than the degree of rotation of the

- axle or driving shaft 18, nor can the differential mechanism in the outer wheel rotate any faster. Consequently, the necessary acceleration of the outer wheel, required in 5 turning the curve, causes the intermediate ring 34 to be moved in a direction of the worm gear 41, but against the tension of the springs 43, these springs eliminating the degree of movement of the intermediate ring 10 in the direction just mentioned. However, the ring is moved the requisite distance to allow the outer wheel together with the ring 44 to ratchet over the teeth 46 of the intermediate ring.
- 15 It is of course obvious that the power transmitted to either wheel is through the axle or driving shaft 18, to the cap 28, which imparts motion to the sleeve 21 and the intermediate ring 34. The teeth on the worm 20 gear 41 are also disposed at an angle which prevents the rollers 40 carried by the floating ring 35 from passing from the left side of the worm gear to the opposite side thereof while the wheels are moving in a forward 25 direction, this construction and arrangement being illustrated in Figure 10, but when it is desired to reverse rotation of the wheels, the intermediate ring 34 is of course rotated in a reverse direction, and the angularity of 30 the teeth at one side of this wheel which meshes with the teeth 47 on the ring 44, forces the intermediate ring in the direction of the worm gear 41. Now, the angularity of the teeth of the gear 41, allows the rollers 40 to pass therebetween, and in this 35 manner the floating ring is shifted to the opposite side of the worm gear. Incident to this movement of parts, the springs 43 are compressed, and the springs 42 relieved 40 of their tension. It is manifest however, that under no circumstances, can one wheel spin in advance of the other, when the latter mentioned wheel is retarded in its movement by becoming stuck in the mud or for any 45 other reason, inasmuch as the power is equally transmitted to both wheels, thereby providing a two wheel drive.
- While it is believed that from the foregoing description, the nature and advantages 50 of the invention will be readily apparent, I desire to have it understood that I do not limit myself to what is herein shown and described, and that such changes may be resorted to when desired as fall within the 55 scope of what is claimed.
- Having described the invention what is claimed is:
1. A clutch mechanism including a driving element, spaced annuli encircling the latter, an intermediate annulus, means whereby said annulus is allowed interlocking engagement with either of said annuli, means for shifting said annulus in either direction, and including a floating ring, a 60 plurality of inwardly directed radially mounted rollers carried thereby, a fixed element having diagonally arranged slots therein through which the rollers pass upon rotation of the driving element in either direction, such movement disengaging the intermediate annulus from one spaced annulus and engaging the intermediate annulus with the other spaced annulus, and resilient means normally urging the floating ring to a position to either side of the fixed element. 65
2. A clutch mechanism including a driving element, spaced tooth annuli encircling the latter an axially shiftable ring arranged between said annuli, a floating ring associated therewith, cooperating elements, one of which is fixed and the other carried by said floating ring and normally disposed at one side of the fixed element to hold the floating ring in a position where the axially shiftable ring will engage one of the spaced annuli, and said fixed element having parallel grooves therein for the passage of the element carried by the floating ring upon rotation of the driving element in one direction. 70
3. In a clutch mechanism including a shaft, a driving element, spaced annuli encircling the latter, an intermediate annulus mounted for sliding movement between said annuli, reversely disposed teeth arranged at the opposite sides of the intermediate annulus and cooperating with said annuli, whereby the intermediate annulus is moved into or out of locking relation with either of said spaced annuli, depending on the direction of rotation of said shaft, means for shifting said intermediate annulus, and including a floating ring, slidable rods having their ends slidably associated with said spaced annuli, and fingers carried thereby for interlocking engagement with said floating ring. 75
4. A clutch mechanism including a shaft, a driving element, spaced annuli encircling the latter, each having angularly disposed teeth at one side thereof, an intermediate annulus mounted for sliding movement between said spaced annuli reversely disposed inclined teeth at the opposite sides of said intermediate annulus for interlocking relation with the teeth of either of said spaced annuli, the teeth of the respective spaced annuli operating to move the intermediate annulus in one or the other direction depending upon the direction of rotation of said shaft, means controlling the movements of said intermediate annulus and including a fixed worm gear, a floating ring associated with said intermediate annulus, and rollers carried by said ring and adapted to pass between the teeth of said gear from one side to the other thereof when the shaft is rotated in one direction. 80
- In testimony whereof I affix my signature.
- HERMAN L. DOUVE.
